UNITED STATES PATENT OFFICE.

CHARLES EDMUND KELLS, JR., OF NEW ORLEANS, LOUISIANA.

ELECTRO-MAGNETIC CLUTCH.

SPECIFICATION forming part of Letters Patent No. 443,772, dated December 30, 1890.

Application filed March 31, 1890. Serial No. 346,073. (No model.)

To all whom it may concern:

Be it known that I, CHARLES EDMUND KELLS, Jr., a citizen of the United States, residing at New Orleans, in the parish of Orleans and State of Louisiana, have invented 5 certain new and useful Improvements in Electro-Magnetic Friction Brakes or Clutches, of which the following is a specification.

The object of my invention is to provide 10 electro-magnetic devices for instantly stopping machinery connected with a power-shaft.

My invention while involving certain improved organizations of instrumentalities is not confined to the details of construction 15 hereinafter described.

The accompanying drawings show several ways of embodying my invention.

Figure 1 is a vertical longitudinal section 20 through the clutch mechanism, the power-shaft being in elevation. Fig. 2 is a similar view showing a modification. Fig. 3 is a similar view showing a further modification, and Fig. 4 is a plan view of still another modification.

25 Referring first to Fig. 1 of the drawings, the main or power shaft A may be mounted and driven in any suitable way. I have shown my improved clutch mechanism mounted on one end of the shaft. The shaft A extends 30 through a bracket B, which is provided with an arm C, to which is attached the electro-magnet E, which may be of any suitable construction. It is shown as consisting of a coil e arranged within a tubular metallic casing e', through which the shaft A extends. The end e² of this casing constitutes 35 one pole of the magnet. The armature F is secured to one end of a sleeve G, which extends through the tubular magnet and is free 40 to slide on the shaft A. The gear-wheel or pulley H, which communicates power from the shaft A to the machinery, is secured to the end of the sleeve opposite that which carries the armature F. A friction-block I is 45 secured to the casing of the magnet, and, as shown, is formed with an inclined or tapered friction-surface i, which may engage with a correspondingly-shaped flange h of the pulley H. A friction-collar J is rigidly secured 50 to the main shaft A on the opposite side of the pulley H. This collar is provided with a friction-surface j adapted to engage with the

corresponding surface on the flange h' of the wheel H. Between the wheel and the collar is interposed a spring K, which tends to hold 55 the wheel H in engagement with the friction-block I, and also hold the armature F away from the magnet. When thus held by the spring, and as shown in the drawings, the main power-shaft A may rotate without rotating 60 the wheel H; but when the magnet E is energized the armature F will be attracted, and will thus move the wheel H away from the friction-block I against the force of the spring K into engagement with the friction-collar J, 65 and the wheel will be revolved with the shaft. As soon as the electric circuit is broken the electro-magnet E is demagnetized and the spring K will force the wheel H out of engagement with the friction-collar J and into 70 engagement with the stationary block I, thus instantly stopping the wheel and the machinery connected therewith.

In Fig. 2 I have shown a tubular magnet E similar in construction to that just described and rigidly secured to a bracket B, in which the power-shaft A has a bearing. An arm C, in this instance shown as secured to the casing of the magnet, extends over the wheel or pulley H, and on the end of this arm 80 is journaled a friction-wheel I', which is held against rotation by a pin I², extending through the arm C. The wheel or pulley H is in this instance shown as formed of magnetizable material and is interposed between the friction-wheel I' and the magnet E. The inner end H' of the hub of the wheel H is formed with a tongue h², adapted to engage with a recess h³ in a friction-block L keyed to the shaft A. Normally the wheel is held by a spring K 90 out of engagement with the friction-block L and in engagement with the friction-wheel I'. When the magnet is energized, the pulley is drawn toward the magnet and the tongue h² engages with the recess h³. The wheel H is 95 thus caused to revolve with the power-shaft. As soon as the magnet is de-energized the pulley H assumes the position shown in the drawings and instantly ceases to rotate. A friction-collar L' is interposed between the block 100 L and the bracket B to take up wear and receive the thrust of the wheel H on the block L.

In Fig. 3 the tubular magnet E is secured to an arm C, attached to a bracket B, through

which the shaft A extends, and a clutch-block I² is rigidly secured to the shaft. The wheel or pulley II is interposed between the clutch-block and the magnet and is normally held 5 in engagement with the clutch-block by a spring K, which bears at one end against a collar k fast on the shaft A. When the magnet is energized, the pulley II is disengaged from the power-shaft and drawn against the 10 end of the magnet, which acts as a brake to instantly stop the revolution of the wheel.

A slight modification is shown in Fig. 4. In this instance a U-shaped or double electro-magnet E is secured to a bracket B, through 15 which the shaft A extends. The wheel or pulley II is normally held by a spring K in engagement with an ordinary toothed clutch-block K², fast on the shaft A. When the magnet is energized, the pulley II is withdrawn 20 from the clutch-block K² and ceases to rotate, being held in engagement with the pole-pieces of the magnet.

I have shown several ways of embodying 25 my invention, but other ways might be suggested. Obviously the details of construction might be changed without departing from the novel features of my invention.

I claim as my invention—

1. The combination, substantially as hereinbefore set forth, of a power-driven shaft, a 30 wheel or pulley loosely mounted thereon, an electro-magnet, its armature, connections between the armature and the wheel, a spring

for holding the armature away from the magnet, a friction-block with which the wheel 35 engages when the armature is withdrawn from the magnet, and a friction-collar with which the wheel engages when the magnet attracts its armature.

2. The combination, substantially as hereinbefore set forth, of the power-driven shaft, a gear-wheel mounted thereon, a friction-collar rigidly secured to the shaft and adapted to engage with the wheel, a stationary friction-block also adapted to engage with the 45 wheel, and electro-magnetic devices for causing the wheel to engage with either the stationary block or the friction-collar.

3. The combination, substantially as hereinbefore set forth, of a power-driven shaft, a 50 wheel or pulley mounted thereon, a tubular magnet through which the shaft extends, its armature, a sleeve extending through the magnet and connecting the wheel with the armature, a stationary friction-block, a friction-collar secured to the shaft, and a spring for holding the wheel in engagement with the stationary friction-block when the magnet is de- 55 energized.

In testimony whereof I have hereunto sub- 60 scribed my name.

CHARLES EDMUND KELLS, JR.
